UNITED STATES PATENT OFFICE.

HARRY R. VAN DEVENTER, OF SUMTER, SOUTH CAROLINA, ASSIGNOR TO SPLITDORF ELECTRICAL COMPANY, OF NEWARK, NEW JERSEY, A CORPORATION OF NEW JERSEY.

TRIPPING MECHANISM FOR IGNITERS.

1,245,832.

Specification of Letters Patent.

Patented Nov. 6, 1917.

Original application filed March 27, 1915, Serial No. 17,499. This application filed November 11, 1916. Serial No. 130,836.

To all whom it may concern:

Be it known that I, HARRY R. VAN DEVENTER, a citizen of the United States, residing at Sumter, in the county of Sumter 5 and State of South Carolina, have invented certain new and useful Improvements in Tripping Mechanism for Igniters, of which the following is a specification, reference being had to the accompanying drawing.

10 The invention relates to new and useful improvements in igniter mechanisms for internal combustion engines and more particularly to the tripping mechanism therefor. In a co-pending application, Serial No. 15 17,499, filed March 27, 1915, I have shown, described and claimed an operating mechanism for operating the igniter and also the magneto for generating a current for ignition, together with a tripping device for the 20 operating mechanism. The present invention is a division of this co-pending application and relates more particularly to an operating mechanism for the igniter, regardless of the source of the current for said igniter.

25 An object of the invention is to provide an igniter operating mechanism wherein a trip lever may be utilized for actuating the igniter and manually actuated means may be used for moving the trip lever against the 30 force of a tension means, tending to normally hold the trip lever in a given position, so as to cock and automatically release said trip lever and also to provide means for holding the trip lever in a cocked 35 position together with manually operated means for releasing the trip lever at will; as for example in the starting of the engine.

40 In the drawings which show by way of illustration one embodiment of the invention:

Figure 1 is a view partly in section and partly in plan showing my improvement applied to an engine.

Fig. 2 is a front elevation thereof.

45 In the drawings the engine cylinder is indicated at 1. This engine cylinder is shown in section in Fig. 1 of the drawings. The igniter body is indicated at 2, said igniter body carries the movable contact 3 and the 50 fixed contact 4 which constitute the usual make and break igniter mechanism. A flange 5 extends around the aperture in the cylinder, and extending from this flange and preferably integral therewith are the arms 55

6 and 7. Studs 8 and 9 are carried respectively by the arms 6 and these studs are provided with rollers 10 and 11, respectively. A spring 12 is connected to the roller 10, while a spring 13 is connected to the roller 11. The other ends of these springs are attached 60 to rollers suitably connected to the trip lever 14. This trip lever 14 is loosely mounted on the shaft 15 of the movable electrode 3. It is understood that the shaft of the electrode forms a support for the trip lever 14 but 65 does not move therewith. The trip lever 14 is formed with an igniter fire finger 16 and a trip finger 18. This trip finger is adapted to be engaged by the push rod 19. The outer end of the push rod is suitably connected to 70 some moving part of the engine, so that the rod has a reciprocating movement over the pulley 20 which causes the inner end 21 of the rod to push inwardly against the trip finger 18 until the same is suddenly released 75 and rides over said finger as is customary in this type of device.

The shaft 15 of the movable contact 3 of the igniter carries an arm 22 at the outer end which is provided with suitable adjusting means such as a screw 25 whereby the relative position of the arm 22 and the firing finger 16 on the trip lever may be adjusted.

A spring 24 or other suitable means may be employed to hold the contacts of the igniter together, which is accomplished by securing one end of the spring to the flange 5 and the other end thereof to the arm 22. A suitable electrical connection 29 leads from a 80 source of current to the binding post 31 on the outer end of the fixed contact 4 of the igniter. This fixed contact is suitably insulated from the igniter body in the usual manner. The circuit is completed through the movable contacts 3 of the igniter and the 85 frame of the igniter mechanism and the other terminal of the current supplying means. This current supplying means may be

90 a magneto operated by the mechanism which operates the igniter or may be a battery or 100 any other suitable current generating means. As the push lever 19 moves forward, the trip lever will be oscillated, moving the arm 16 of the trip lever away from the 105 arm 22 of the movable electrode contact and the spring 24 will hold the contacts in engagement. When the trip lever is released then the arm 16 will strike the arm 22 and

quickly separate the contacts, thus producing the spark for ignition. To prevent the operation of the igniter mechanism during the idle strokes of the engine the exhaust 5 valve push rod 32, which has a reciprocating motion is provided with suitable means, such as a pin 33 adapted to engage the arm 34 of a bell crank lever. The upper end 35 of the bell crank lever is positioned under the push 10 rod 19 so that when the exhaust rod is actuated, which occurs during the idle stroke of the piston on "hit-and-miss" engines, or when the exhaust is held open by the governor, the bell crank lever will be shifted so 15 as to lift the push rod 19 above the finger 18 and this prevents the operation of the igniter mechanism as the rod 19 will reciprocate idly above the finger 18 without engaging the same.

20 I have also provided a shaft 36 upon which the pulley 20 is eccentrically mounted when the arm 37 is moved to the right or the left. As viewed in Fig. 2 the end of the push rod 19 is raised or lowered in its relation to the finger 18 thereby varying the time of ignition. For the purpose of operating the magneto by hand I have provided a lever 38 which is pivoted on the post 9, and said lever is provided with an operating 25 handle 39. The lever 38 is of such length as to engage the stud 40 and raise the same into the position indicated in dotted lines in Fig. 2, under which condition the lever also assumes the position indicated in dotted lines. In raising the stud 40 into the dotted line position the trip lever 14 is swung into its maximum operating or cocked position. In order to hold the trip lever in this cocked position, an extension 42 is provided on the trip lever and this extension is 30 so arranged as to engage a trigger 43 when said trip lever is in cocked position. The trigger 43 is pivotally mounted on a post 8 and is controlled by a weight 44 which normally turns the trigger in a clockwise direction. The trigger may be turned in the opposite direction by a suitable handle 45. It is obvious from the foregoing that, under 35 normal conditions, when the lever 38 is rotated in a clockwise direction through approximately 270° then said trip lever will be thrown into cocked position and automatically locked there during engagement of the end of the extension with the trigger 43.

40 With the trigger mechanism latched in cocked position, all that is necessary, in order to start the engine, is to turn the same into the power stroke, and then release the trigger 43 by operation of the handle 45 whereby the ignition mechanism is actuated 45 under force of the operating springs 12 and 13 so as to separate the contacts, produce a spark and ignite the charge. As soon as the engine is started the handle 45 is placed in substantially a horizontal position, thereby

raising the trigger 43 out of engaging relation with the trip lever extension 42 and the trigger will be held in this position by the weight 44 which is moved to the left of the vertical, passing through the pivot of said 70 trigger.

To stop the engine it is only necessary to place the trigger back in the position indicated in Fig. 2, whereupon the next throw of the trip lever into cocked position, by the 75 normal operation of the push rod, will cause it to become latched in that position and stop the engine, leaving the ignition mechanism set in readiness for again starting the engine by releasing the trigger. 80

It is further noted that in initially starting the engine, with the igniter parts in normal or uncocked position, the trigger 43 may be disabled, as previously pointed out, and the trip lever 14 thrown into its extreme 85 operative position and then released or tripped by continued rotation of the lever 38 in a clockwise direction. This operation will, of course, have the same effect of producing the spark and starting the engine. 90

While I have herein described and illustrated in detail the preferred embodiment of my invention, it is to be understood that various modifications may be made without departing from the spirit of the invention, 95 as set forth in the appended claims.

Having thus described my invention, what I claim and desire to secure by Letters Patent is:

1. Ignition mechanism for an internal combustion engine comprising a frame adapted to be mounted on the engine, an igniter carried by the frame so as to extend into the ignition chamber of the engine, a trip lever for actuating said igniter, tension means extending between the frame and trip lever tending normally to maintain the trip lever in a given position, manually actuated means carried by the frame for moving the trip lever against the force of said tension means to cocked position and automatically releasing the same, means carried by the frame for holding the trip lever in cocked position against the force of said tension means, and manually operated means carried by the frame for releasing the trip lever. 100

2. Ignition mechanism for an internal combustion engine comprising a frame adapted to be mounted on the engine, an igniter carried by the frame so as to extend into the ignition chamber of the engine, a trip lever for actuating said igniter, tension means extending between the frame and trip lever tending normally to maintain the trip lever in a given position, means operated by the engine for moving the trip lever against the force of said tension means to cocked position and automatically releasing the same, manually actuated means carried by 105

- the frame for moving the trip lever to cocked position and automatically releasing the same, means carried by the frame for holding the trip lever in cocked position
- 5 against the force of the tension means, manually actuated means carried by the frame for releasing the trip lever, and means carried by the frame for disabling said holding means.
- 0 3. Ignition mechanism for an internal combustion engine comprising a frame adapted to be mounted on the engine, an igniter carried by the frame so as to extend into the ignition chamber of the engine, a trip lever for actuating said igniter, tension means extending between the frame and trip lever tending normally to maintain the trip lever in a given position, means operated by the engine for moving the trip lever against the force of said tension means to cocked position and automatically releasing the same, means carried by the frame for holding the trip lever in cocked position against the force of the tension means, manually actuated means carried by the frame for releasing the trip lever, and means carried by the frame for disabling the said holding means.
4. Ignition mechanism for an internal combustion engine comprising a frame adapted to be mounted on the engine, an igniter carried by the frame so as to extend into the ignition chamber of the engine, a trip lever for actuating said igniter, tension means extending between the frame and trip lever tending normally to maintain the trip lever in a given position, means operated by the engine for moving the trip lever against the force of said tension means to cocked position and automatically releasing the same, means carried by the frame for timing the release of the trip lever, manually actuated means carried by the frame for moving the trip lever to cocked position and automatically releasing the same, means carried by the frame for holding the trip lever in cocked position against the force of the ten-
- sion means, manually actuated means carried by the frame for releasing the trip lever, and means carried by the frame for disabling said holding means.
5. Ignition mechanism for an internal combustion engine comprising a frame adapted to be mounted on the engine, an igniter carried by the frame so as to extend into the ignition chamber of the engine, a trip lever for actuating said igniter, tension means extending between the frame and trip lever tending normally to maintain the trip lever in a given position, means operated by the engine for moving the trip lever against the force of said tension means to cocked position and automatically releasing the same, manually actuated means carried by the frame for moving the trip lever to cocked position and automatically releasing the same, trigger mechanism pivoted on the frame for automatically catching and holding the trip lever in cocked position after the movement of the trip lever to said position and releasing it at will, and means for disabling said trigger mechanism.
6. Ignition mechanism for an internal combustion engine comprising a frame adapted to be mounted on the engine, an igniter carried by the frame so as to extend into the ignition chamber of the engine, a trip lever for actuating said igniter, tension means extending between the frame and trip lever tending normally to maintain the trip lever in a given position, engine actuated means and manually actuated means carried by the frame for moving the trip lever against the force of said tension means to cocked position and automatically releasing the same, trigger mechanism pivoted on the frame for automatically catching and holding the trip lever in cocked position upon its movement into said position and releasing it at will, and means for disabling said trigger mechanism.

In testimony whereof I hereunto affix my signature.

HARRY R. VAN DEVENTER.
